CLAIM

The ornamental design for a garlic roller, as shown and described.

DESCRIPTION

FIG. 1 is a perspective view of the garlic roller in a closed state;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is an additional perspective view of the garlic roller in a closed state.

FIG. 9 is a perspective view of the garlic roller in an open state;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is an additional perspective view of the garlic roller in an open state.
